United States Patent Office.

ORRIN LUCE, OF CORTLAND, NEW YORK.*

Letters Patent No. 83,647, dated November 3, 1868.

IMPROVEMENT IN TRUNK-HINGES.

The Schedule referred to in these Letters Patent and making part of the same.

To all whom it may concern:

Be it known that I, ORRIN LUCE, of Cortland, in the county of Cortland, and State of New York, have invented a new and useful Improvement in Box or Trunk-Hinges; and I do hereby declare that the following is a true and exact description of the construction and operation of the same, reference being had to the accompanying drawings, making a part of this specification, and in which a perspective view of the hinge is given.

This hinge is intended to be used or applied in the corners of the trunk, and screwed or fastened both to the end and back of the trunk, in the inside.

a is a flap or wing of the lower part of the hinge, to be screwed on to the lower end piece of the trunk.

s is another wing of the hinge, at right angles to *a*, and fastened to the back of the trunk.

g g being projections from *a* and *b*, and extending far enough to allow the hinge-bolt *x*, passing through them, to be about in a line with the outside surface of the trunk.

b t are corresponding wings or flaps, forming the upper part of the hinge, and attached to the upper ends and back pieces of the trunk, with a projection, *p*, which works between the projections *g g*, and through which the hinge-bolt passes.

d is a segment of a circle, whose centre is at the

hinge-bolt, cast upon the inner side of the wing *a*, and extending above it.

c is a projection from the wings *b t*, working in the segment, and, when the trunk is closed, dropping into the recess *o*.

e is a knob or rest upon the inner surface of the segment *d*, against which the projections *c* may catch or rest as the hinge or trunk opens. This knob is so placed as to catch the point of *c* when the trunk-lid shall have a little passed the perpendicular, and will there hold it, preventing the lid falling back too far, and dispensing with any strap.

This hinge being screwed to both the ends and back of the trunk at the corners, makes the corners stronger, both of the bottom and lid-portions of the trunk, and the hinges are less liable to strain and split the wood than the ordinary hinge put on at points intermediate the corners.

I claim, and desire to secure by Letters Patent—

The construction and arrangement, herein described, of the parts *a*, *s*, *b*, *t*, *g g*, *p*, *d*, *e*, and *c*, for the purpose set forth.

ORRIN LUCE.
